UNITED STATES PATENT OFFICE.

ISAAC S. MCGIEHAN, OF JERSEY CITY, NEW JERSEY, ASSIGNOR TO THE
ATWOOD RAILWAY WHEEL COMPANY, OF NEW YORK, N. Y.

CAR-COUPING.

SPECIFICATION forming part of Letters Patent No. 243,594, dated June 28, 1881.

Application filed May 5, 1881. (Model.)

To all whom it may concern:

Be it known that I, ISAAC S. MCGIEHAN, a citizen of the United States, and residing at Jersey City, in the State of New Jersey, have 5 invented a new and useful Improvement in Car-Couplers, of which the following is a specification.

The object of my invention is to provide means by which cars may be coupled and uncoupled automatically, so that the necessity of going between the cars in order to couple or uncouple them may be obviated, and at the same time to arrange and construct the coupler so that cars of different heights may be 15 coupled and uncoupled automatically.

Reference being had to the accompanying drawings, Figure 1 represents a plan of my coupler when the cars are coupled. Fig. 2 represents a side elevation. Fig. 3 represents 20 a front view of the coupler.

In the figures of the drawings, A represents the casings, which act as a covering for the more intricate parts.

On one side of the outer end of each casing 25 A is situated a shoulder, C. These shoulders must be so constructed as to extend vertically above and below the casings A.

As shown in Figs. 2 and 3, B is the draw-bar attached to the casings A, and having at 30 the outer end the hook I.

My object in extending the shoulders C above and below the casings A is to provide ample means for properly receiving the hook I when the cars to which the coupler may be 35 attached should be of different heights. It will thus be seen that the hook I of one coupler is made to fit into the shoulder C of the opposite coupler. It will also be seen by reference to the drawings that the hook I and 40 the shoulder C should be of the shape there shown, in order that they may fit snugly.

At the other end of the draw-bar B is the arm J, constructed for the purpose of confining the spring, indicated by F and shown in 45 Fig. 1. The draw-bar B, arm J, and hook I are of one entire piece, having a hole through which passes the bolt R for the purpose of securing it to the casings A, as shown in Fig. 1.

D is a block, of elliptical form, between the 50 casings A, having an eccentric movement, and

O is a shaft which extends vertically through its center. This shaft is connected, either above or below the casings A, with the handle G, which may be drawn to the opposite side of the car by means of a rod, and the effect of 55 its operation will be to throw the elliptical block or eccentric D to its greatest diameter.

E is a lever-arm having one end hinged to the casing A, which is shown at P, while the other end is left free to be operated upon and 60 to be forced outwardly by the action of the elliptical-shaped block or eccentric D, acting by means of the handle G, against the hook I.

F is a spring which fits tightly between the arm J and the block K, and its operation is 65 to throw the draw-bar B into its position again after having been uncoupled by means of the eccentric D and the handle G.

H represents a link, and h a pin, which are ordinarily used to couple cars, and which may 70 be used, in connection with my device, to couple with another car not provided with my improvement.

K represents a block attached to the casings A, and having a socket on one side to 75 hold one end of the spring F.

The operation of my car-coupler is as follows: By turning the handle G by means of a rod attached to it and reaching to the opposite side of the car the elliptical block or eccentric D is caused to revolve to a position where its diameter is the greatest. When it has reached this position it will have acted on one side on the lever E so as to force it outwardly and against the hook I of the opposite coupler, and on the other side it will force out of its position the draw-bar B. This operation instantaneously detaches the draw-bars B from the shoulders C. This is one way of uncoupling the cars; but I do not wish in this 90 invention to confine myself entirely to this one method, because the uncoupling may be done in another way. By extending the shaft O to the top of the car, and there operating it by proper means, the uncoupling will be just as readily 95 effected as in the former method. Upon releasing the handle G the elliptical block or eccentric D will again assume its original position, and the spring F will throw the draw-bar B again into its place, so that when the 100

couplers come together again the hook I of the draw-bar B will strike against the beveled face of the shoulder C belonging to the opposite coupler, and be thrown outward, to be again forced into its position behind the shoulder C by means of the force communicated to it from the spring F.

I do not claim in this specification those parts which are known to be old, and which it is unnecessary for me to enumerate; but

What I do claim, and desire to secure by Letters Patent, is—

1. The combination of the casing A, having on one side of its outer end a shoulder, C, constructed as hereinbefore described, with the draw-bar B, constructed as described above, the elliptical-shaped block or eccentric D, in

connection with the lever E, the handle G, spring F, and the shaft O, substantially as described and set forth.

2. The combination of the casing A, having on one side of its outer end a shoulder, C, constructed as hereinbefore described, with the draw-bar B, having on one end the hook I, and on the other end the arm J extending at right-angles from said draw-bar, all forming one entire piece, in connection with the spring F and block K, as and for the purposes described.

I. S. McGIEHAN.
